UNITED STATES PATENT OFFICE.

BARNES NEVILLE WALLIS AND CHARLES DENNISTON BURNETT, OF WESTMINSTER,
LONDON, ENGLAND, ASSIGNEES TO AIRSHIP GUARANTEE COMPANY, LIMITED, OF
WESTMINSTER, ENGLAND, A BRITISH COMPANY.

LIGHTER-THAN-AIR AIRCRAFT

Application filed September 17, 1927, Serial No. 220,245, and in Great Britain September 17, 1926.

This invention relates to lighter-than-air aircraft.

When it is desired to effect any repairs to the engines of existing airships, which are of such a nature that they cannot be carried out in situ, or to remove and replace an engine, it is necessary before the engine car can be lowered to the ground, to disconnect it not only from the drag and suspension wires, but also from the controls, fuel pipes, electric wires, water pipes, telegraph and telephone cables, etc. leading from the car to the airship.

According to the present invention the engine car of an airship is constructed in two or more sections, comprising a permanent section to which the drag wires and suspension wires are connected and which surrounds the access trunk, said permanent section, containing the radiator, controls telegraphs, starting engine, or other permanent fixtures or connections to the airship, and a removable section which contains the engine and its propeller, and which is detachably connected to the permanent section so that, when necessary, it can be removed without disturbing the controls and fixtures etc. in the permanent section. Instead of a single removable section two removable sections may be provided and located at each end of the permanent section each section containing an engine and its propeller, and each section being detachably connected to the permanent section. In cases where each engine car has a pair of engines and forward and rear propellers a single radiator may also be provided in the centre portion, or the permanent section, and located at the hull of the car in the slip stream between both engines, the radiator being adjustable so that it can be raised or lowered relatively to the hull of the engine car.

In order that the said invention may be clearly understood and readily carried into effect, the same will now be described more fully with reference to the accompanying drawing in which:

Figure 1 is a partly diagrammatic elevation of an engine car constructed according to one embodiment of the present invention and provided with a permanent section and two detachable sections.

Figure 2 is a plan view, and Figure 3 is a sectional end view of Figure 1.

A is the permanent section of the engine car. B is the detachable front or forward portion of the engine car, and C is the detachable rear portion of the engine car. The permanent section A of the engine car is connected by means of suspension tubes a , a , to the hull of the airship and two drag wires a' , a' and two anti-drag wires a^2 , a^2 are also provided extending as shown from the engine car to the hull of the airship. a^3 is the access trunk by which communication is established between the permanent section A of the engine car and the airship. The access trunk a^3 contains the requisite ladders, fuel pipes, controls, telegraph and telephone cables, electric wires and piping etc., extending between the permanent section A of the engine car and the airship. The detachable forward portion B is provided with an engine b and propeller b' and is detachably secured to the permanent section A in any suitable manner for example, by means of ball joints b^1 , b^2 . The detachable portion C is provided with an independent engine c and propeller c' and, in a similar manner to the section B it is detachably connected to the said section A by means of ball joints c^1 , c^2 of any suitable construction. c^3 , c^4 are two suspension tie rods, which are adapted to be uncoupled at their ends when the rear portion C is being removed. b^3 is one of the tie rods also provided at the front portion B. The permanent section A is fitted with a radiator a^4 adapted to be raised or lowered relatively to the hull of the engine car. The radiator a^4 is shown in full lines at Figures 1 and 3, in the lowered position where it is situated in the slip stream of the forward propeller b' and in dotted lines at Figure 1 when in the raised position within the permanent section A. As the radiator a^4 is situated in the slip stream it is subjected to a relatively high wind speed so that a single radiator of smaller area than those previously provided for a pair of engines can be employed. Furthermore, if the forward engine b stops the radiator a^4 provides a sufficient cooling area for the rear engine c , while if the rear engine c stops, the radiator can be raised into the permanent portion A of the engine car so as to reduce the surface exposed to the wind stream. The centrally located and permanent portion A of the engine car may be provided with attachments

or other fixtures for accommodating a winch, shear legs, pulleys, etc., so that the detachable engine section can be supported from the permanent section while being detached therefrom and lowered away. In the example shown a pair of shear legs d , d are provided, the lower ends of which are adapted to be temporarily secured to fixtures in the permanent section A. The shear legs d , d carry a pulley d' and a pulley block d^2 from which the winding rope d^3 extends to a winch d^4 , mounted, in the example shown, in the top of the dynamo E in the permanent section A. The top cowling c^4 of the portion B is removable in the way of the shear legs d , d , d^4 is a tie rod for the shear legs d , d , which is temporarily secured to the permanent portion A while fixing the shear legs in position. A similar arrangement of fittings for a pair of shear legs is also provided for dealing with the removable section B.

The detachable portions B and C of the engine car may be provided with buffers or preferably with attachments for a set of wheels (not shown) so that prior to the removal of the said detachable portions B and C the wheels can be located on the axle sockets or other bearings provided therefor.

30 The engine car can then be lowered by the shear legs d , d onto the wheels which fulfill the combined function of acting as buffers and also enabling the detachable portion of the engine car which contains the engine to be wheeled away.

By reason of the present invention an engine and its propeller can expeditiously be removed from the engine car of an airship without interfering with the controls, 40 fuel pipes, electric wires, water pipes, telegraphs and telephone cables or the like which run from the airship to the engine car or without disconnecting the suspension and drag wires. Furthermore, it reduces the weight of the part which has to be lowered to the ground enables a section containing a new engine to be rapidly attached in position in place of a section containing a damaged engine, and, in cases where a pair of engines are provided, as in the example illus-

trated, it admits of the use of a single radiator arranged in the slip stream between the propellers so that a radiator of smaller size than has heretofore been necessary to cool a pair of engines can be employed.

What we claim and desire to secure by Letters Patent of the United States is:—

1. An engine car for an airship, comprising a permanent section to which the drag wires and suspension wires are connected and which surrounds the access trunk to the airship and a removable section which contains the engine and its propeller and which is detachably connected to the permanent section so that when necessary it can be removed without disturbing the controls and fixtures etc. in the permanent section.

2. An engine car for an airship, comprising a permanent section to which the drag wires and suspension wires are connected and which surrounds the access trunk to the airship and two sections located respectively at each end of the permanent section, each of said sections containing an engine and its propeller and being detachably connected to the permanent section.

3. An engine car for an airship, provided with a pair of engines and with forward and rear propellers, together with a single radiator located at the hull of the engine car in the slip stream between both engines, the radiator being adjustable so that it can be raised or lowered relatively to the hull of the engine car for the purpose specified.

4. An engine car for an airship as claimed in claim 1, in which the detachable portion thereof is provided with buffers.

5. An engine car for an airship as claimed in claim 1, in which the detachable portion thereof is provided with attachments for a set of wheels for the purpose specified.

6. An engine car for an airship as claimed in claim 1, in which the permanent section is provided with means for accommodating a winch, shear legs, pulleys and the like so that the detachable engine section can be supported from the permanent section, while being detached therefrom and lowered away.

BARNES NEVILLE WALLIS,
CHARLES DENNISTON BURNEY.
